CLAIM

The ornamental design for a vibration element for a haptic actuator, as shown and described.

DESCRIPTION

FIG. 1 is a front view of a vibration element for a haptic actuator of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a sectional view taken along lines 8-8 in FIG. 1;

FIG. 9 is a perspective view thereof showing the vibration element for a haptic actuator in use.

FIG. 10 is a front view of a second embodiment of a vibration element for a haptic actuator of the present invention;

FIG. 11 is a rear view thereof;

FIG. 12 is a top plan view thereof;

FIG. 13 is a bottom view thereof;

FIG. 14 is a right side view thereof;

FIG. 15 is a left side view thereof;

FIG. 16 is a perspective view thereof;

FIG. 17 is a sectional view taken along lines 17-17 in FIG. 10;

FIG. 18 is a perspective view thereof showing the vibration element for a haptic actuator in use.

FIG. 19 is a front view of a third embodiment of a vibration element for a haptic actuator of the present invention;

FIG. 20 is a rear view thereof;

FIG. 21 is a top plan view thereof;

FIG. 22 is a bottom view thereof;

FIG. 23 is a right side view thereof;

FIG. 24 is a left side view thereof;

FIG. 25 is a perspective view thereof;

FIG. 26 is a sectional view taken along lines 26-26 in FIG. 19; and,

FIG. 27 is a perspective view thereof showing the vibration element for a haptic actuator in use.

The features shown in broken lines depict environmental subject matter only and form no part of the claimed design.
